UNITED STATES PATENT OFFICE.

ADOLF W. KEUFFEL, OF MONTCLAIR TOWNSHIP, ESSEX COUNTY, NEW JERSEY, AS-
SIGNOR TO KEUFFEL & ESSER COMPANY, OF HOBOKEN, NEW JERSEY, A CORPORA-
TION OF NEW JERSEY.

DRAWING INSTRUMENT.

Application filed April 26, 1922. Serial No. 556,787.

To all whom it may concern:

Be it known that I, ADOLF W. KEUFFEL, a citizen of the United States, residing at 763 Bloomfield Avenue, in the township of

5 Montclair, in the county of Essex and State of New Jersey, have invented certain new and useful Improvements in Drawing Instruments, of which the following is a specification:

10 This invention relates to an improvement in drawing instruments, and the novelty consists in the adaptation and arrangement of the parts, as will be more fully hereinafter pointed out.

15 It has been found essential in the construction of compasses or dividers to have the two legs secured together so that there will always be an even tension in the legs on moving them apart or closing them together, so that they will remain in the position desired by the operator. It has also been found essential that the handle of the compass or divider should also be under an independent uniform tension so that the 20 handle would remain in the position desired by the operator irrespective of the position of the legs.

25 My device not only solves this difficulty by furnishing a pair of fork arms which are mounted under a uniform tension independently of the tension of the legs, but also furnishes a suitable joint in both legs so that the lower leg may be set perpendicularly to the paper, thereby giving the instrument a 30 symmetrical appearance and a perfect balance. My device also furnishes leg joints of even tension which do not require adjustment.

35 Referring to the drawing Figure 1 is a front elevation of my dividers; Figure 2 is a side elevation of the same; Figure 3 is a front elevation of my compasses, and also showing in dotted outline the legs spread apart and with the lower legs in the perpendicular position; Figure 4 is a side elevation of the same; Figure 5 is a perspective of the spring used in connection with the handle of the compass and divider; and Figure 6 is a sectional detail of the head of the legs and the mounting of the handle of my compass and divider.

40 In the drawings 7 and 8 are cylindrical tapered legs of the dividers shown in Figures 1 and 2, which have shoulder members 45 9 and 10 respectively, and said shoulders 9

and 10 have mounted therein pins 48 and 49, respectively, each terminating in pintles 11 and 48, over which the spring fork arms 12 slide having recesses 13 into which the pintles 11 are adapted to register and be held by the spring pressure of the arms 12. The pin 49 is also long enough to extend into the opening in the shoulder 9, in which pin 48 is mounted and thereby serves to align the shoulders 9 and 10 perfectly. A spring 60 14 having a slot 15 and a hole 16 is adapted to be mounted between the arms 12 so that a screw 17, mounted in the lower end of said arms 12 so as to hold the same together in a fixed position, also passes through the hole 70 16 in said spring 14, and the slot 15 slides over the pintle 11 so that the spring 14 effects a constant spring pressure between the shoulder 10 and the arm 12, thereby effecting a uniform tension on the fork arms 75 12. A fluted handle 18 is rigidly secured to the fork arms 12. The shoulder 10 has a pocket 19 adapted to contain lubricant to facilitate the easy operation of the legs 7 and 8. The leg 7 has an insert arm 20 of 80 usual construction secured at the head by a screw 21 and at the base by a knurl-headed adjusting screw 22, all of which is constructed for the purpose of quick and minute adjustment of the leg 7. Needles 23, which have been previously hardened to the condition required, are mounted by a drive-fit in borings 24 in the base of the legs 7 and 8. The legs 7 and 8 also have circular cut-outs 25 which are adapted to facilitate the operator in the handling of the dividers. 90

95 In Figures 3 and 4 is shown a compass having upper legs 26 and 27 which are also cylindrical and tapered, and to these are joined lower cylindrically tapered legs 28 and 29 respectively, said lower legs having circular shoulders 30 and tongue members 31 integral therewith. Said tongue members 31 are adapted to fit into grooves 32, which grooves 32 are extended by a narrower groove 33, so as to give more spring to the members 34 formed by the grooves 32. Said members 34 and the tongues 31 have internal threaded borings 35 adapted to receive tapered screws 36. This construction permits the tapered screws 36 to be adjusted so that the hinges formed by the tongues 31 and grooves 32 may be readily used without further adjusting of screws 36. The lower legs 28 and 29 have borings 37 at their lower 100 105 110

ends, and gripping members 38 effected by means of a slot 39 and bosses 40 which are rigidly secured to the members 38 and are internally threaded at 41, in which a knurled set screw 42 is adapted to be screwed, and needle or pencil points 43 are adapted to be mounted in said slots 37 as the set screw 42 is loosened and the needle or pencil points 43 are rigidly retained in working position by turning down the set screw 42, thereby drawing the members 38 together to hold 43 in rigid position. The construction of shoulders 9 and 10 and the fork arms 12 and the connecting parts are all the same in the compass shown in Figs. 3 and 4 as in the dividers shown in Figs. 1 and 2, and the spring 14 is mounted in the same way for the same purpose. The upper leg 27 has a separate part 44 near its base which is detachable from the upper leg 27, and has a pentagonal shank 45 which fits a similar socket 46 in the base of the upper leg 27, and a knurled set screw 47 is mounted in the upper leg 27 so as to hold the shank 45 rigidly in position in the socket 46, but permitting the disjoining of these parts when desired so that other parts may be mounted therein.

The cylindrical tapered form of the legs of my compasses and dividers facilitates in the handling of the instrument, as this form of leg fits the hand of the operator readily, and the spring 14 gives the fork arms 12 with the handle 18 an independent tension at all times, which will not be varied by the changes in tension of the legs 7 and 8 or 26 and 27.

I claim:

1. In a drawing instrument the combination of two cylindrical tapered legs having circular shoulders adapted to fit together, pintles projecting from each of said shoulders outwardly, a fork head with two

spring arms adapted to snap over said pintles and having recesses on the inside adapted to receive the same, and a screw to fasten the lower end of said fork arms together.

2. In a drawing instrument the combination of two cylindrical tapered legs having circular shoulders adapted to fit together, pintles projecting from each of said shoulders outwardly, a fork head with two spring arms adapted to snap over said pintles and having recesses on the inside adapted to receive the same, and a screw to fasten the lower ends of said fork arms together, and means for effecting an independent uniform tension on said fork head.

3. In a drawing instrument the combination of two cylindrical tapered legs having circular shoulders adapted to fit together, pintles projecting from each of said shoulders outwardly, a fork head with two spring arms adapted to snap over said pintles and having recesses on the inside adapted to receive the same, and a screw to fasten the lower ends of said fork arms together, and means for effecting an independent uniform tension on said fork head consisting of a spring mounted between said shoulders and said fork head so as to maintain a uniform pressure against said fork head.

4. In a drawing instrument the combination of two legs having shoulders adapted to fit together, means for maintaining alignment of said shoulders, a fork head having arms adapted to snap over said shoulders, means for pivoting said shoulders between said fork arms, means for adjusting the tension on said shoulders, and independent means for maintaining a uniform tension on said fork arms.

In testimony whereof I affix my signature.

ADOLF W. KEUFFEL,
